JOINT FOR ARTIFICIAL LIMBS

Emil Schwarzkopf, Los Angeles, Calif.

Application February 26, 1945, Serial No. 579,765

6 Claims. (Cl. 287—96)

1

This invention relates to a joint for an artificial body member, and more particularly to an ankle joint that connects an artificial foot member to the lower extremity of an artificial leg.

Generally, ankle joints for this purpose are well-known. It is one of the objects of this invention to improve in general joints of this character.

It is another object of this invention to ensure that the joint will remain adequately lubricated and freely movable, and without producing any annoying creaks.

In this way, dismantling of the artificial members for relubrication is entirely obviated even after long periods of service.

This invention possesses many other advantages, and has other objects which may be made more clearly apparent from a consideration of one embodiment of the invention. For this purpose, there is shown a form in the drawings accompanying and forming part of the present specification. The form will now be described in detail, illustrating the general principles of the invention; but it is to be understood that this detailed description is not to be taken in a limiting sense, since the scope of this invention is best defined by the appended claims.

Referring to the drawings:

Figure 1 is a diagrammatic side elevation of an artificial foot and ankle member incorporating the invention; and

Fig. 2 is an enlarged sectional view, taken along plane 2—2 of Fig. 1, some of the elements being broken away to reduce the size of the figure.

There is indicated the lower end 1 of an artificial leg to which is jointed an artificial foot 2. The joint is so arranged that the foot 2 may be moved about an axis 3, corresponding in position to the ankle joint. Motion of the artificial foot 2 is restrained about the axis 3 by the aid of the structure illustrated most clearly in Fig. 2.

One element of the joint structure is a pin member 4 that has a cylindrical exterior surface. It is attached to the artificial leg 1 as by the aid of a pair of studs 5 and 6. These studs have axes transverse to the axis 3, and are spaced apart to provide a sufficiently rigid support for the member 4. The lower ends of these studs 5 and 6 may be threaded appropriately into the pin 4.

In order to provide a sufficiently large seat for holding the joint structure in position with respect to the artificial leg 1, there are attached to the ends of the member 4 a pair of extensions 7 and 8. Although these members are shown as

made of separate pieces, telescoping over the ends of pin 4, such a structure is not essential.

Extensions 7 and 8 are provided with appropriate through apertures 9 for the passage of the studs 5 and 6. In this way, the members 7 and 8 are retained against removal from pin 4. The exterior surfaces of extensions 7 and 8 can rest upon appropriate saddle surfaces attached to the leg member 1.

10 The exterior cylindrical surface of member 4 serves as the inner ball race for two sets of balls 10 and 11. These two sets of balls are arranged symmetrically about an axis 12 of a fastening bolt 13. This bolt is arranged to extend downwardly into an aperture in the artificial foot 2 and to be fastened therein as by nut 30.

Fastening bolt 13 has a hollow cylindrical head 14 through which the member 4 extends. In the interior of the head there is an inwardly directed annular flange 15. This flange serves to separate the two sets of balls 10 and 11 and also serves to provide outer ball races.

25 The balls 10 and 11 are confined against appreciable axial movement by the inner surfaces 16 and 17 of the members 7 and 8. Lubricant, such as grease or the like, may be packed around the balls 10 and 11. The pin 4 is prevented from axial movement by the engagement of balls 10 and 11 with the flange 15. Lubricant retaining 30 rings 18 and 19 are provided, having inwardly directed flanges overlapping respectively the flanges 20 and 21 formed at the inner ends of the members 7 and 8. These rings are press fitted over the cylindrical portions 22 and 23 at 35 the sides of the hollow head 14. A sealing ring 24 of cork, or the like, is interposed between the ring 18 or 19 and the face of the extension 22 or 23. These rings 24 extend inwardly to overlap the flanges 20 and 21 and, therefore, confine the 40 lubricant to the hollow head 14.

Once the joint structure is packed with lubricant, there is no substantial loss of lubricant from the hollow head 14. Accordingly, the necessity of dismantling the joint for relubricating is obviated.

The inventor claims:

1. In a device of the character described: a pin member; extensions at each end of the pin member, each of said extensions having an outwardly facing annular shoulder adjacent the inner end of the extension; means for fastening said pin member to an artificial leg, including a pair of studs transverse to the axis of the pin; a bolt having a hollow head through which the pin member passes, said head having an inter-

mediate flange, co-operating with the inner ends of said extensions and the pin to define a pair of ball races; balls in said races; and retaining rings carried respectively by the opposite sides of the head and having portions co-operating with said shoulders on the extensions for sealing the space in the head.

2. In a device of the character described: a pin member; extensions at each end of the pin member; means for fastening said pin member to an artificial leg, including a pair of studs transverse to the axis of the pin; a bolt having a hollow head through which the pin member passes, said head having an intermediate flange, co-operating with the inner ends of said extensions and the pin to define a pair of ball races; balls in said races; said extensions having exterior shoulders substantially co-planar with the opposite sides of the head; a sealing ring overlapping the shoulder and the side of the head for each extension; and retaining rings attached respectively to opposite sides of the head for holding said sealing rings in place.

3. In a device of the character described: a pin member; extensions at each end of the pin member, each of said extensions having a transverse aperture; means for fastening said pin member to an artificial leg, including a pair of studs transverse to the axis of the pin and passing respectively through said apertures in the extensions; a bolt having a hollow head through which the pin member passes, said head having an intermediate flange, co-operating with the inner ends of said extensions and the exterior surface of the pin to define a pair of ball races, respectively on opposite sides of the flange; balls in said races; said extensions having shoulders substantially flush with the respective sides of the hollow head; a pair of retaining rings pressed onto the head and extending inwardly; and sealing rings extending over the shoulders and the sides of the hollow head, and held in sealing relationship by the retaining rings.

4. In a device of the character described: a pin member; extensions at each end of the pin member, said extensions respectively having outwardly facing annular shoulders adjacent their inner ends; means for fastening said pin member to an artificial leg, including a pair of studs transverse to the axis of the pin member; a bolt

having a hollow head through which the pin member passes; means forming a radial and thrust bearing between said hollow head and said pin member; and retaining rings carried respectively by the opposite sides of the head, and having portions co-operating with said shoulders on the extensions for sealing the space in the head.

5. In a device of the character described: a pin member; extensions at each end of the pin member; means for fastening said pin member to an artificial leg, including a pair of studs transverse to the axis of the pin; a bolt having a hollow head through which the pin member passes; means forming a radial and thrust bearing between said hollow head and said pin member; said extensions respectively having exterior shoulders substantially coplanar with the opposite sides of the head; a sealing ring overlapping the shoulder and the side of the head for each extension; and retaining rings attached respectively to opposite sides of the head for holding said sealing rings in place.

6. In a device of the character described: a pin member; extensions at each end of the pin member; means for fastening said pin member to an artificial leg, including a pair of studs transverse to the axis of the pin; a bolt having a hollow head through which the pin member passes; means forming a radial and thrust bearing between said hollow head and said pin member; said extensions having shoulders substantially flush with the respective sides of said head; a pair of retaining rings pressed onto the head and extending inwardly; and sealing rings extending over the shoulders and the sides of said head, and held in sealing relationship by the retaining rings.
